(57) **CLAIM**

The ornamental design for a gone smoking indicator, as shown and described.

DESCRIPTION

FIG. 1 is a left-side elevational view of the gone smoking indicator of my invention;

FIG. 2 is a front-elevational view thereof;

FIG. 3 is a rear-elevational view thereof;

FIG. 4 is a right-side elevational view thereof;

FIG. 5 is a bottom-plan view thereof;

FIG. 6 is a top-plan view thereof;

FIG. 7 is a perspective view thereof;

FIG. 8 is a perspective view thereof as used with a coffee cup;

FIG. 9 is a perspective view thereof as used with a wine glass;

and,

FIG. 10 is a perspective view thereof as used with a beer bottle.

In the drawings, the broken lines represent environment that

form no part of the claim.
